UNITED STATES PATENT OFFICE.

WILLIAM H. SOMMER, OF PEORIA, ILLINOIS, ASSIGNOR, BY MESNE ASSIGNMENTS, TO THE FIRST TRUST AND SAVINGS COMPANY, OF CLEVELAND, OHIO, A CORPORATION OF OHIO, AND WILLIAM E. STONE, OF PEORIA, ILLINOIS, TRUSTEES.

WIRE-WORKING MACHINE.

1,264,987.

Specification of Letters Patent.

Patented May 7, 1918.

Application filed January 31, 1916, Serial No. 75,345. Renewed March 14, 1918. Serial No. 222,503.

To all whom it may concern:

Be it known that I, WILLIAM H. SOMMER, a citizen of the United States, residing at Peoria, in the county of Peoria and State of Illinois, have invented new and useful Improvements in Wire-Working Machines, of which the following is a specification.

This invention has reference to certain new and useful improvements in wire working machines, and particularly to that type of fabricating machines used in the manufacture of farm, field and poultry fences.

Reference is had to patent issued to me on April 14, 1914, No. 1,093,578 for improvements in wire-feeding mechanism. This patent describes and shows such a wire working machine as I have reference to, and for purposes of illustration and disclosure I have incorporated into this application certain of the parts or devices shown in said patent.

One of the objects of the present invention is to improve the clutch-controlled mechanism included in the feeding means for the stay feed wire.

A further object of the invention is to provide a stay wire feeding mechanism for feeding alternately a long stay wire and a comparatively short stay wire, whereby, a fence fabric may be manufactured having alternately arranged long stay wires extending from one selvage or marginal wire to the other selvage or marginal wire, and comparatively shorter stay wires extending from one selvage or marginal wire to a certain intermediate strand or line wire of the fence fabric. A fence so constructed combines a field and hog fence in the one fabric.

The invention has for a further object to connect the intersections of the stays and longitudinal strand wires by means of suitable wire ties, the mechanism for feeding the tie wire stock from which said wire ties are severed including means for feeding the tie wire stock to a predetermined number of the intersections of each succeeding long and short stay wires included in the fence fabric, and other means for feeding tie-wire stock to a predetermined number of the intersections of only the long stay wires included in the fence fabric. In other words, the mechanism for feeding tie-wire stock to the intersections of the short stay wires will op-

erate with the placing of not only the short stay wires across the fence fabric, but also with the placing of the long stay wires across said fabric and in timed relation thereto, while the mechanism for feeding tie-wire stock to the intersections of the long stay wires with a predetermined number of the longitudinal strand wires will operate only at the intervals of placing said long stay wires across said fence fabric, and in timed relation thereto.

Figure 1 is a partial plan view of a certain type of wire fabricating machine showing my improvements applied thereto;

Fig. 2 is a side elevation of the machine looking in at the left hand side of Fig. 1, the stay feed wire feeding mechanism shown in the position just prior to the completion of the feeding of a long stay wire;

Fig. 3 is a vertical longitudinal sectional view through the machine to show more particularly the relation of the longitudinal strand wires and the stay wires crossing the same, also the manner of feeding in the tie-wire stock for providing the wire from which the tie-wire sections are severed, used to connect the intersections of the stays and strands.

Fig. 4 is an enlarged fractional sectional view of the clutch controlled mechanism for the feed;

Fig. 5 is a face view of a cam wheel coöperating with the clutch mechanism of the feed, and

Fig. 6 is an edge view of the cam wheel shown in Fig. 5;

Fig. 7 is a detail view of the means controlling the feeding of the stay feed wire, the parts being in a position just preceding the beginning of the feeding of a long stay;

Fig. 8 is a view similar to Fig. 7, except that the parts are shown in a position just preceding the feeding of a short stay.

Fig. 9 is a detailed front elevation of the means for controlling the feeding of the stay feed wire;

Fig. 10 is a plan view of Fig. 9;

Fig. 11 is a cross-section as the same would appear if taken on the line 11-11 of Fig. 9 looking in the direction of the arrow on said figure;

Fig. 12 is an end elevation as the same

would appear looking in at the left hand side of Fig. 9;

Fig. 13 is a cross-section in plan as the same would appear if taken on the line 5 13—13 of Fig. 9;

Fig. 14 is a cross-section as the same would appear if taken on the line 14—14 of Fig. 13, looking in the direction of the arrow on said figure;

10 Fig. 15 is a cross-section as the same would appear if taken on the line 15—15 of Fig. 13, looking in the direction of the arrow on said figure;

15 Fig. 16 shows in detail the gearing and cams included in the means for controlling the feeding of the stay feed wire;

Fig. 17 is a detail side elevation of the tie-wire stock feeding means employed for feeding tie-wire stock for the intersections 20 of only the long stay wires with the strand wires;

Fig. 18 is a perspective view of the ratchet-toothed wheels and pawl used in the mechanism shown in Fig. 17;

25 Fig. 19 is an elevation of the gearing and ratchet-toothed wheel mechanism shown in Fig. 17;

Fig. 20 is a cross section showing the detail structure of the parts illustrated in 30 Fig. 19 and their relation to each other;

Fig. 21 is a view of a piece of fence fabric such as is made on the machine herein shown, and

35 Fig. 22 is a diagrammatic view illustrating in a graphic way the feeding of the long and short stay wires and the feeding of the tie-wire stock thereto.

Like characters of reference denote corresponding parts throughout the figures.

40 In my former Patent No. 1,093,578, to which reference has been made, a feature of the inventive idea was the intermittent clutch controlled feeding means actuated by mechanism, which, when it acted upon

45 the stay feed wire, started said stay feed wire at a slow speed, gradually increasing until the momentum of the wire reached its maximum speed, and gradually decreasing until the complete stay length had been

50 fed, the highest speed of the wire being attained at the point when one-half of the desired length of stay had been fed. This feature of invention is included in the present improvements, or rather, the present

55 improvements in the mechanism for feeding alternately long and short stays is included in the means for feeding the stay wire in the manner just previously stated, and associated with said stay wire feeding means,

60 is an improved mechanism for feeding tie-wire stock from which the wire ties are severed, used for connecting the intersections of the stay and the strand wires.

65 In the drawings, I have shown my improved stay feed wire mechanism and tie-

wire stock feeding means applied to that type of wire fabricating machine employing die mechanism for clenching wire ties around the intersections of the stay wires with the intermittent longitudinal running 70 or strand wires, and coilers for wrapping or winding the ends of the stays around the marginal or selvage wires, with the exception that the upper ends of the short stay wires are connected to a certain intermediate strand wire by wire ties the same as is used for connecting the intermediate body portions of the long and short stay wires 75 with intermediate strand wires.

The machine is illustrated in a general 80 way for the purpose of showing the application of my invention thereto, and reference may be had to the Sommer Patent No. 1,078,702, dated Nov. 18, 1913, for detailed views of the die mechanisms and coiling 85 means such as is used in the machine herein disclosed. These details form no part of the invention herein, but merely cooperate in forming a complete fabricating machine.

90 It will become apparent that my improvements, as herein described and claimed, may be applied to fabricating machines other than the kind herein illustrated, and I do not wish to be confined to the application of 95 the invention to a machine such as shown.

The framework of the machine comprises in part the base members 1, the uprights 2 supporting the table 3; the standards 4, 5, and 6, and the cross piece 7. The parts 100 designated 1, 2, 5 and 6 are duplicated upon opposite sides of the machine and on the part 1 is supported the platform 8 on which an operator may stand.

9 designates a drive shaft and 10 a timing 105 shaft, both of which are suitably journaled in bearings on the uprights 2. The driving shaft 9 is adapted to receive its power from some suitable source, such as a line shaft or direct drive from a motor, and it in turn 110 is adapted to operate the timing shaft 10 through gear wheel 11 on the timing shaft (see Fig. 3), which will mesh with a gear wheel on the timing shaft, not shown.

14 designates a crank shaft suitably journaled in the frame and on said crank shaft is a sprocket wheel 15 engaged by a sprocket chain 16 which is driven by a sprocket wheel 17 on the timing shaft 10, said sprocket chain passing over an idler 18 carried by the 120 upright 4. It will be observed that the driving shaft 9, when in operation, transmits motion to the timing shaft 10 and it in turn drives the crank shaft 14 through the 125 sprocket chain 16 and sprocket wheels 17 and 15, respectively.

19 designates a wrapper shaft journaled in suitable bearings at the rear end of the machine, and said wrapper shaft 19 is driven from the crank shaft 14 by means of a 130

sprocket pinion 20 on the crank shaft, a sprocket chain 21, and a sprocket wheel 22 on the wrapper shaft.

23 refers generally to a die mechanism, 5 preferably including wire tie cutting and forming means and means for clenching the wire ties around the intersections of the stay wires and the intermediate strand wires. The details of this mechanism are immaterial, as no special stress is laid on the individual parts of the wire connecting mechanism, and as stated, reference may be had to the Sommer Patent, No. 1,078,702 for details of the preferred form of structure. 10 15 The mechanism for feeding the tie-wire stock to the wire connecting mechanism is material, forms a part of the present invention, and will be hereinafter more particularly described. 20 25 24 designates the end coilers, one for each of the selvage or marginal wires of the fence fabric, and associated with each of said coilers is a cutting and depressing mechanism 25, although the stay feed wire feeding mechanism when properly adjusted for the feeding of the stay wires is such that the cutting mechanism at the far side of the machine from the in-feed of the stay feed wire is not necessary, and only the cutter 30 mechanism at the in-feed side of the machine is necessary, whereby a stay length may be severed from the stay feed wire. The details of this cutting and depressing mechanism are clearly shown in the Sommer 35 Patent No. 1,078,702. In operation, the cutting mechanism will sever a stay length C from the stay feed wire B, and the depressing mechanism will depress the ends of the stay wire C down onto the coilers 24 in 40 position to be engaged by the pins of the coilers for wrapping or coiling the ends of the long stay wires around the selvage or marginal wires, and one end of the short stay wires around one of said selvage or 45 marginal wires.

The strand wires A, which are fed from reels, spools or other suitable means, not shown, pass preferably around a roller 27 on a spindle 28 and up through suitable 50 openings in the table 3. The wires A which serve as the marginal or selvage wires pass up through the coilers 24, and the wires A, serving as the intermediate running or strand wires, pass through the die mechanism 23, as shown in Fig. 3.

The stay feed wire B which may be fed from a bundle, spool, or in any suitable manner, passes through the straightening rollers, referred to generally as 30, and thence between the intermittently driven friction feed wheels 31 and 32, and leaving said feed wheels, passes through suitable guides adjacent to the cutter and depressor 25 across the coiler or spindle 24 and through the die mechanisms, as shown in Figs. 1 and

3. The said feed wire B, as shown, passes between the friction feeding wheels 31 and 32, which engage the wire to feed it endwise across the machine. These feeding wheels may be grooved to receive the wire 70 B, or not, as may be desired. The feed wheel 31 is the driving wheel of the feed, and the wheel 32 is the driven wheel. In other words, when power is applied to the wheel 31, it will impart movement to the wheel 32 75 through the engagement of such wheels with the wire B which is frictionally held between the same. The wheel 31 is carried on a shaft 33 which has a relatively fixed position with reference to the shaft 34 on which 80 the wheel 32 is carried, and the shaft 34 is journaled in a frame 35 fulcrumed at 36, and spring means 37^a engaging the forward end of the frame 35 yieldingly holds the wheel 32 in frictional engagement with the 85 wheel 31; the object of which is, to allow the wheel 32 to move relatively to the wheel 31 to accommodate the various sizes of said feed wires B which it may be desired to use in the fabric. 90

On the shaft 33 carrying the wheel 31 is also carried a gear wheel 37, said gear wheel 37 and feed wheel 31 being suitably connected so that when movement is imparted to one, such movement will be concurrently and simultaneously imparted to the other. The gear wheel 37 meshes with a much larger clutch controlled gear wheel 38. The gear wheel 38 is of that construction, best seen in Figs. 1 and 4, wherein said wheel has the internal circumferential friction clutch-engaging face 39, and said gear is further provided with the enlarged depending hub 40, said hub being journaled on a bushing 41 carried on a vertically disposed tubular casing 42 suitably carried by the upright 2, shown in Figs. 2 and 4. 95 100 105

43 designates a tubular shaft which has a bearing in the vertical casing 42, see Fig. 4, said casing 42 having the lower and upper 110 inner bushings 44 and 45 in which the tubular shaft 43 has a bearing; said tubular shaft 43 having the plug 46 at its lower end and the similar plug 47 at its upper end, which serve as bearings in which is carried and 115 through which moves the vertically movable stem 48, which at its upper end and above the bearing 47 is secured in the hub 49 of the wheel 50 having the peripheral friction face 51 adapted to have a friction engaging relation with the clutch-engaging face 39 of the gear wheel 38. The rim and the hub of the wheel 50 are connected by the arms or spiders 52, two or more of which are provided with the tubular bosses 53 in which are secured rods or stems 54, for purposes to be explained. On the upper end of the tubular shaft 43, and within the gear wheel 38 and below the body portion of the wheel 50, is a plate or disk-like member 55; said 120 125 130

plate or disk-like member being secured to the upper end of the tubular shaft 43, whereby it may rotate with said tubular shaft. Said plate or disk-like member 55 is provided with two or more bosses 56 in which the lower ends of the rods or stems 54 are carried and movable, so that when said plate or disk-like member 55 is rotated through and by means of the tubular shaft 43, such movement will in turn be imparted to the wheel 50 through the connections between said wheel and said plate or disk-like member, described. When the wheel 50 is raised through the movement of the vertical stem 48, which said movement is very slight, it will in turn elevate the rods or stems 54, without disengaging said rods or stems from said plate or disk-like member 55. From the foregoing description, it will be observed, that if the stem 48 is raised, it will in turn elevate the wheel 50, disengaging the friction gripping surface on the rim of the wheel 50 from the frictional clutch engaging surface 39 of the gear wheel 38, bringing about an inoperative relation between said wheel 50 and said gear wheel 38. Upon the stem 48 being lowered, the wheel 50 will in turn be lowered, moving the friction gripping surface 51 of said wheel 50 into impinging relation with the clutch gripping surface 39 of the gear wheel 38, whereby if the tubular shaft 43 is rotated, such rotative movement will be imparted to said gear wheel 38 through the wheel 50 and the plate or disk-like member 55. The wheel 50 is moved from friction clutch-engaging relation with the gear wheel 38 to its disengaged position, by the upward movement of stem 48, as just described, and when said stem 48 is raised, it is moved against the tension of a spring 57 carried on the upper end of rod 58, (see Figs. 2 and 4,) and disposed between washers 59, the lower of which bears against the hub of the wheel 50, and the upper of which is held in position by means of the nuts 60 on the end of the rod 58. This rod extends down into the vertically movable stem 48 a suitable distance and is secured to a transversely disposed stem 61 passing through slots 62 in the wall of the stem 48, and the opposite ends of the stem 61 secured in the walls of the tubular shaft 43. Thus it will be seen that as the stem 48 is raised, it will contract the spring 57 and as soon as the means for raising the stem 58 is released to allow the stem to return to its lower or normal position, the spring 57 will expand, forcing the stem 48 downwardly and with it the wheel 50, bringing about a friction clutch-engaging relation between the friction gripping faces of the wheel 50 and the gear wheel 38.

The means for rotating the tubular shaft 43, as will be described, is such that said tubular shaft is rotated alternately, first, in

one direction and then in an opposite direction. When said tubular shaft is rotated in one direction the plate or disk-like member 55, the wheel 50, gear wheel 38 and the feed wheel 31 will rotate concurrently and simultaneously through and by means of the connections described; but when the said tubular shaft 43 is rotated in an opposite direction, the gear wheel 38 and the feed wheel 31 with which it is geared, are inoperative by reason of the separation of the clutch engaging faces 51 of the wheel 50 and 39 of the wheel 38 resulting from the raising of the stem 48, in manner described.

On the lower end of the tubular shaft 43 and below the casing 42 (see Fig. 4) is carried a gear wheel 63 and said gear wheel is in mesh with and adapted to be driven alternately in opposite directions by the rack-bar 64. Said rack-bar is movable in the guide 65, coincident with the gear wheel 63 and at its inner end said rack-bar 64 is secured to a slidable head 66 having, preferably, a dovetailed connection with and movable on a bar 67, (see Fig. 2), said bar 67 supported by a bracket 68 at one end secured to the part 1, and at its opposite end secured upon an arm 69 attached to the upright 4. It is obvious that any movement which is imparted to the rack-bar 64 will be in turn imparted to the gear wheel 63 and the shaft 43 to which said gear wheel is attached. When the rack-bar 64 is moved forward, or in the direction indicated by the arrow in Fig. 2, the stem 48 is in its lowermost position, being in that position shown in Fig. 4, and the clutch engaging face 51 of the wheel 50 is in clutch engaged relation with the clutch engaging face 39 of the gear wheel 38 and said gear wheel will rotate concurrently and simultaneously with the wheel 50, the tubular shaft 43 and the gear wheel 63. Such movement will also be imparted to the gear 37 and in turn to the feed wheels 31 and 32 for the purpose of projecting the stay feed wire B across the machine preparatory to the operation of the cutter and depressor 25 for severing a stay length C. When the rack-bar 64 is moved in an opposite direction to that just described, mechanism will be brought into play for elevating the stem 48, which will in turn raise the wheel 50 and by such movement separate the clutch engaging surface 51 on the wheel 50 from the clutch engaging surface 39 on the wheel 38, and stop the rotation of said gear wheel 38. The alternate forward movement of the rack-bar 64 and the operation of the gear wheel 63 is such that only sufficient movement will be imparted to the gear wheel 38, to rotate the feed wheels 31 and 32 to feed the stay feed wire a sufficient distance for delivering long and short stays C of the proper length, and that immediately upon the gear wheel 38

being stopped in its rotation, the cutter 25 will be operated to sever a short or a long stay length C from the stay feed wire B. The rack-bar actuating mechanism includes 5 adjusting means, as will be described, for regulating the stroke of the rack-bar to insure the feeding of long and short stays of proper length.

Pivottally connected at 70 with the slidable head or block 66 is a pitman bar or rod 71 and said bar or rod has a pivotal connection at 72 with a plate 73 slidably carried on a casting 74 keyed on the crank shaft 14. The plate 73 has a substantial dovetail connection with the casting 74 (see Fig. 11), and such connection while permitting of a slid- 10 able relation between said plate and said casting, holds the plate true during its move- 15 ment back and forth on said casting. To 20 provide for the pivotal connection between 25 said pitman bar or rod 71 and the plate 73, said plate has a stem 75 projecting there- 30 from, formed with two shoulders 76 and 77. On said stem between the shoulder 76 and 35 the body of the plate 73, is carried a collar 78 having a threaded stem 79, and on said 40 stem 75 between the shoulders 76 and 77 is carried the end of the pitman bar or rod 71, whereby a pivotal relation is produced 45 between said pitman bar or rod 71 and 50 said plate 73. That portion of the stem 75 between the shoulder 77 and the extreme outer 55 end 75 of said stem is threaded as at 80 to receive a nut 81 for holding the collar 78 and the end of the pitman bar or rod 71 in 60 operative connection with said stem. The casting 74 is formed with a hub or bearing portion 82, about which encircles a segment gear 83, said gear being stationary while 65 the casting 74 is rotatable. This segment gear 83 is in juxtaposition to a cam plate 84, and said cam plate and said segment gear wheel 83 are bolted or otherwise suitably secured to the standards 5 and 6. On the 70 rear end portion of the casting 74 and lo- 75 cated on the outside face thereof is rotatably carried a plate 85, said plate having a hub 86. Journaled in said casting, and having a bearing in said hub 86 of the plate 85 is a 80 hub 87 of a gear wheel 88, said gear wheel and said plate 85 being connected so as to 85 rotate together, by means of the bolt 89 passing through said plate 85 and gear wheel 88 and with a nut 90 secured on the end 90 of said bolt, the plate 85 and the gear wheel 88 being suitably recessed to receive the head 95 of the bolt, and also the nut, as best seen in Fig. 13. Secured to the rear face of said gear wheel 88, by bolts or other suitable 100 means, is a plate 91 having the friction bear- 105 ing surfaces 92, (see Fig. 16). The gear wheel 88 is so disposed on the rear face of the casting 74 that during each complete 110 rotation of the casting 74 with the crank shaft 14, the gear wheel 88 will intermit- 115

tently engage with the teeth of the segment gear 83 and rotate the plate 85 one-half rev- 120 olution. The engagement of the teeth of the gear wheel 88 with the teeth of the segment gear wheel 83 will take place during one- 125 half revolution of said casting 74, and dur- 130 ing the remainder of the complete revolution of said casting 74, the friction bearing surfaces 92 on one side of plate 91 will en- 135 gage and ride on the cam surface of the plate 75 84, holding the plate 85 in the position just 140 previously moved by the intermeshing of the teeth on the gear wheel 88 with the 145 teeth of the segment gear wheel 83. The 150 gear wheel 88 is provided with diametrically 155 disposed master teeth 93 to impart the initial 160 movement to said gear wheel 88 and the 165 plate 85, when said master teeth move into 170 engagement with the first tooth of the seg- 175 ment gear 83.

The pitman bar or rod 71 which actuates the gear wheel 63 through the rack-bar 64, is reciprocated through the rotary movement imparted to the casting 74 by the rotation of the crank shaft 14, and the length of the 180 stay wire C is determined by the position of the plate 73 and its stem 75 (to which is pivotally connected the pitman bar or rod 71) with respect to the axis of the crank 185 shaft 14 by means of which the plate 73 is 190 rotated. In other words, the closer to the axis of the crank shaft 14 is carried or positioned the stem 75, the shorter will be the stroke of the rack-bar 64, and the farther from the axis of the said crank shaft 14 is 195 carried or positioned the stem 75, the greater the stroke of the rack-bar 64. A short stroke of the rack-bar 64 will produce a short stay wire C and a long stroke of the 200 rack-bar 64 will produce a long stay wire C. 205

In my former Patent, No. 1,093,578, the pitman bar or rod, to which is connected the rack-bar, is shown connected with a crank arm through and by means of which the pitman bar or rod is reciprocated, and said pit- 210 man bar or rod has an adjustable connection with said crank so as to shorten or lengthen the stroke of the pitman bar or rod and with it the rack-bar. The adjustment included in such driving mechanism, in my former pat- 215 ent, was only for the purpose of regulating the length of the stay wire with each differ- 220 ent type of fence to which the machine was adjusted. That is to say, all stay wires were of the same length, reaching from one sel- 225 vage or marginal wire to the other selvage or marginal wire, and the only necessity for adjusting the stroke of the rack-bar would be in the event of a change in the height of the fence. In the present machine the stroke 230 of the rack-bar must be changed with every other stay and this change must be done au- 235 tomatically so that with each alternate stroke of the rack-bar a long and a short stay 240 will be fed into the fabric. I accomplish 245

the alternate feeding of a long and a short stay wire by automatically changing the position of the plate 73 with its stem 75 on the casting 74 during each revolution of the 5 crank shaft 14. That is to say, as the casting 74 is rotated with the crank shaft 14 to impart a reciprocal movement to the pitman rod or bar 71, the gear wheel 88 will mesh with the intermittent gear wheel 83, imparting 10 a one-half turn to the plate 85 and through connections between said plate 85 and the plate 73, which I shall now describe, the position of the plate 73 with its stem 75 may be moved closer to or farther from the 15 axis of the crank shaft 14 whereby a short stroke of the rack-bar 64 may be made for the purpose of feeding a short stay wire C, or a long stroke of the rack-bar 64 may be made for the purpose of feeding a long stay 20 wire C.

Having a dovetailed connection with and slidably adjustable on the plate 85 is a head 94, said head formed with an extension 95 to which is suitably connected one end of a 25 threaded stem 96, the opposite end of said stem passing through a bearing plate 97 secured to the end of the plate 85. The end of the threaded stem 96 is squared as at 98, whereby by means of a suitable tool the 30 threaded stem may be operated to adjust the position of the head 94 on the plate 85. Suitably connected with the head 94 is a threaded stem 99; and said stem 99 and the similar stem 79, previously referred to, have 35 a threaded relation in a tubular nut 100, and on said threaded stem 99 is carried a tubular nut 101 serving to lock the position of the threaded stem 99 in the nut 100, and on the threaded stem 79 is a tubular nut 102 40 serving to lock the position of said threaded stem 79 in the tubular nut 100. In each of said nuts 100, 101 and 102 suitable openings or perforations are provided for the insertion of a suitable tool for adjusting the 45 threaded stems 79 and 99 relatively to each other to regulate the position of the plate 73 on the casting 74, and the position of the head 94 on the plate 85, such adjustment increasing or decreasing the length of the stay 50 wire C, when necessary to insure the long stay wire reaching from one selvage or marginal wire of the fence to the other, or from one selvage or marginal wire to a certain intermediate strand wire of the fabric.

55 I will now describe the means for elevating or lifting the stem 48 to separate the clutch engaging surface 51 of the wheel 50 from the clutch engaging surface 39 of the gear wheel 38 when the rack-bar 64 is moved in a direction opposite to that indicated by the arrow on the rack-bar (Fig. 2). On the cam shaft 10 (see Fig. 2), there is carried a wheel 103 having the engaging surfaces 104 and 105, the latter acting as a cam surface 60 and leading and merging into the surface

104 at points 106 and 107. Adapted to engage and roll upon the surfaces 104 and 105 of wheel 103, is a roller 108 carried by an arm 109, which said arm is fulcrumed at 110 on a bracket 111. The arm 109 is formed 70 with a neck 112 carrying a stem 113, which said stem is normally in axial alinement with the stem 48 operatively carried in the tubular shaft 43, and said stems 113 and 48, respectively, are connected by a loose joint 114, 75 (see Figs. 2 and 4). The object of such loose joint is to provide for moving the stem 48 when the arm 109 is operated on its pivot 110, and also to allow the shaft and stem to rotate without disturbing the actuating 80 means for said stem. When the roller 108 is engaging and traveling upon the surface 104 of the wheel 103, the arm 109 is in a position permitting the stem 48 to assume its lowermost position, being that position 85 shown in Fig. 4, where the clutch engaging surface 51 of the wheel 50 is in clutch engaging relation with the clutch surface 39 of the gear wheel 38. When said roller 108 is engaging and traveling upon the surface 105 of the wheel 103, the lower end of the arm 109 has been swung outwardly on its pivot 113, elevating the neck 112, and raising the stem 48 to cause the wheel 50 to be raised, 90 separating the clutch surface 51 of said wheel from the clutch engaging surface 39 of the gear wheel 38 and stopping the rotation of said gear wheel. When the rack-bar 64 is moved in the direction indicated by the arrow on said bar in Fig. 2, the roller 108 is 95 riding on the surface 104 of the wheel 103 and the clutch engaging surface 51 of the wheel 50 is in clutch engaging relation with the clutch surface 39 of the gear wheel 38; immediately upon the rack-bar 64 reaching 100 the limit of its forward stroke, whether it be for a short or a long stay, the off-set portion 106, where the surface 105 of the wheel 103 merges into the surface 104 of said wheel, engages with the roller 108, operating 105 the arm 109 to elevate the stem 48 which will cause the wheel 50 to be raised, separating the clutch engaging surface 51 of said wheel 50 from the clutch engaging surface 39 of the gear wheel 38, and the parts will 110 be held in this position until the rack-bar 64 is moved backward the limit of its stroke and is again ready to be moved forwardly, when the roller 108 will ride off of the surface 105 at the point 107 onto the surface 115 120 104, the arm 109 being oscillated through such movement and through the expansion of the spring 57 which was contracted during the separation of the clutch engaging surfaces as aforesaid, causing the stem 48 to 125 be moved downwardly carrying with it the wheel 50, through the connections previously described, causing the clutch engaging surface 51 of the wheel 50 to enter into clutch engaging relation with the clutch engaging 130

surface 39 of the gear wheel 38, when said gear wheel may be rotated through the driving connection between the tubular shaft 43 and the plate or disk-like member 55 with 5 said wheel 50, previously described.

The surface 105 of the wheel 103 is preferably formed by the arch-shaped wings 115 and 116, (see Figs. 5 and 6,) which are adjustably attached to the rear face of the 10 wheel 103, so that the peripheral face of said sections may be brought together or moved apart, while yet at the same time extending or retracting the surface 105 for the 15 purpose of adjusting or regulating the movement of the arm 109, to conform to the stroke of the rack-bar 64, or to conform to the movement of any other parts of the mechanism with which the same has a timed relation.

20 It will be understood from the foregoing description, that the timing shaft 10 has a one to one relation with the crank shaft 14; that is to say, the timing shaft 10 is geared to make one revolution with each 25 revolution of the crank shaft 14, and vice versa, so that with each stroke of the pitman bar or rod 71 and the rack-bar 64, whether the mechanism is feeding a long 30 stay wire C or a short stay wire C, the wheel 103 on said timing shaft 10 will operate in timed relation thereto to actuate the mechanism for separating the clutch engaging surfaces between wheel 50 and the gear wheel 38, and permit such parts to reengage at proper 35 intervals of time to actuate the feeding mechanism for projecting either a long stay wire C or a short stay wire C across the fence fabric. It is obvious that through the mechanism described for operating the pit- 40 man bar or rod 71 from the crank shaft 14, that during the movement of said pitman bar or rod 71 and said rack-bar 64 to feed a long stay wire C, such parts will move relatively faster than they will move during 45 the feeding of a short stay wire C, and whether operating to feed a long stay wire C or a short stay wire C, the stroke of the pitman bar or rod 71 during the feeding movement will be made during the one com- 50 plete rotation of the timing shaft 10, whereby the parts controlling the separation and engagement of the clutch engaging surfaces between the wheel 50 and the gear wheel 38 will be actuated so as to insure the separa- 55 tion of such clutch engaging surfaces after the feeding of each long and short stay wire C.

The long and short stay wires C where they intersect with the intermediate strand wires A of the fence fabric are connected thereto by means of staple-like tie-members D. These tie-members are first severed from tie-wire stock E, said tie-wire stock being intermittently fed to each of the in- 60 tersections of the long and short stay wires

C with the intermediate strand wires A, and when so severed are connected to said crossed wires where they intersect, by suitable wire connecting mechanism, previously designated as 23. For a more detailed description of the tie-wire stock feeding mechanism and the wire connecting mechanism, reference may be had to the Sommer Patent No. 1,078,702. However, by reference to Figs. 17 to 20 the feeding mechanism for the tie-wire stock may be seen, such as used on that side of the machine for feeding the tie-wire stock from which the staple-like tie-wire sections are made for the upper portions of the long stay wires 70 C, where they cross the upper series of intermediate strand wires A, (see Figs. 3 and 21), and with slight modifications the mechanism shown in Figs. 17 to 20 is used on the other side of the machine for feeding 75 the tie-wire stock from which the staple-like sections are severed used for connecting the lower portions of the long stay wires and the short stay wires C to the series of intermediate strand wires A for that side 80 of the fabric, (see Figs. 3 and 21). This method of feeding the tie-wire stock, that is, a series for one side of the fabric and a series for the other side of the fabric, will 85 produce staple-like tie-wire members which 90 cross the intersections of the wires diagonally and in opposite directions, (see Figs. 3 and 21), but this arrangement in no wise affects the symmetry of the fence or its practicability. 95

Having reference to the tie-wire stock feeding mechanism for both sides of the machine, 117 designates a driving shaft on which is carried a plurality of friction driving wheels 118. This shaft 117 is intermittently operated by means of a pawl 119 pivotally connected between plates 120 loosely carried on said shaft 117, and to said plates is pivotally connected a member 121 which in turn has pivotally connected thereto a 105 pitman bar or rod 122, and said pitman bar or rod is suitably connected to one end of a lever 123 fulcrumed at 124 on the bracket 68, and said lever at its opposite end carries a roller 125 riding against and adapted to 110 be operated by the cam wheel 126 carried on the outer end of the time shaft 10. Thus, with each revolution of the timing shaft 10, the pitman bar or rod 122 will be reciprocated, causing the pawl 119 to engage with 115 a tooth of a ratchet wheel 127 keyed or otherwise suitably secured on the driving shaft 117 between the plates 120, and rotate said shaft to feed in the tie-wire stock E. The feeding of the tie-wire stock E is accom- 120 plished through the feeding wheels 118 and a series of feeding wheels 128 which coöperate therewith, said last-mentioned feeding wheels carried on a driven shaft 129 and internally 125 geared thereto through the internal gears 130

130 on each of the feeding wheels 128, which intermesh with and are driven by a common gear 131 on said driven shaft 129. Said feeding shaft 128 and driving shaft 117 are 5 geared together by means of the intermeshing gears 132 and 133, best seen in Fig. 2. The feeding wheels 128 are adapted to be yieldingly forced into co-operative relation with the feeding wheels 118 for the purpose of feeding the tie-wire stock E, or one 10 or more of said feeding wheels 128 may be released and allowed to run loose when it is desired to cut out the feeding of any one or more of the tie-wire stock wires E. This 15 is accomplished by rotating each feeding wheel 128 in a friction bearing block 134, and engaging each bearing block is a bar 135 which may be caused to bear more or less against the bearing block 134, by means 20 of the adjusting screw 136. The mechanism which I have just described for feeding the tie-wire stock is substantially the same for both sides of the machine. It is necessary, however, to operate the driving 25 shaft 117 on the left-hand side of the machine, looking at Fig. 3, when each long and short stay wire has been fed across the fence fabric, because the tie-wire stock E fed by means of the feeding rollers 118 and 30 128 on this side of the machine, is used to supply the tie-wire stock for the formation and attaching of staple-like tie-wire members for that portion of the long stay wires attached to the corresponding intermediate 35 strand wires A to which the short stay wires are attached; whereas, the tie-wire stock fed by the feeding rollers 118 and 128 on the opposite or right-hand side of the machine, looking at Fig. 3, is only fed when a long 40 stay wire C has been fed across the fence fabric, and such tie-wire stock is used for supplying the wire from which the staple-like tie-wire members are severed used for connecting the upper portions of the stay 45 wires C to the intermediate strand wires A across which the short stay wires C do not extend. In other words, the driving shaft 117 is partially rotated with each alternate movement of the corresponding shaft 117 50 on the other side of the machine, and with every other rotation of the timing shaft 10. I accomplish this through the provision of an additional ratchet toothed wheel 137. This wheel is loosely carried on the driving shaft 107, and preferably upon an extension of the ratchet toothed wheel 127, (see Fig. 20). The ratchet toothed wheel 137 is much larger in diameter than the ratchet toothed wheel 127, (see Fig. 18), but every 55 other tooth of the ratchet wheel 137 is a deep tooth, such as 138, so that the pawl 119 is allowed to engage with only every other tooth of the ratchet toothed wheel 127 and such engagement will occur when the 60

pawl 119 enters a deep tooth 138 on the 65 wheel 137, but when said pawl enters a shallow tooth on said ratchet wheel 137, it will be held from engagement with a tooth on the wheel 127, although the pawl 119 may move and with it will move the ratchet 70 toothed wheel 137 as will be understood. The pawl 119 for this side of the machine is provided with an extension 139 to permit it to have engagement with the teeth of the ratchet toothed wheel 137, (see Fig. 75 18). It is obvious, therefore, that with each alternate movement of the pawl 119 having the extension 139, or when the pawl 119 is engaging with a shallow tooth on the ratchet wheel 137, said pawl will not engage with 80 a tooth on the ratchet wheel 127, and that no movement will be imparted to the driving shaft 117, although the ratchet wheel 137 will rotate thereon, but that when said pawl 119 enters a deep tooth 138 of the 85 wheel 137, said pawl will engage with a tooth on the ratchet wheel 127 and impart a partial rotation to the driving shaft 117 for feeding in the tie-wire stock E.

The ratchet toothed wheel 137 is secured 90 to or forms a part of a sleeve 140, which is carried on the sleeve extension of the ratchet toothed wheel 127, and for yieldingly and frictionally holding said sleeve 140 and ratchet toothed wheel 137 in operative position relatively to the ratchet toothed wheel 127, a threaded stem 141 is secured into the end of the shaft 117 and on said stem is carried a bearing plate 142 adapted to engage the end of said sleeve 140, and said bearing plate 142 is adjustably and yieldingly held in this position by means of a spring 143 coiled about the stem 142, said spring bearing 95 against the plate 142 and against locking and adjusting nuts 144.

The tie-wire stock E is fed to the machine from suitable reels or spools over a roller 145 and through tubes 146, which said tubes for a portion of their length extend transversely across the machine and then diagonally to the wire connecting mechanisms 23, as best seen in Fig. 3.

In Fig. 22 is represented a piece of fence fabric comprising ten longitudinal wires, 115 two of which form the outside marginal or selvage wires and the remainder of which comprise the intermediate strand wires. A standard field fence with ten longitudinal wires would constitute a ten bar forty-seven inch fence. This fence with the long and short stays would combine, as previously stated, a hog and a field fence, that portion of the fence connected by the short stay wires including six longitudinal wires corresponding to a six bar twenty inch fence. 120 The figure illustrates the progressive order 125 in which the short and long stays are attached and the manner of attaching the

same, and the feeding in of the tie-wire stock from the opposite sides of the machine, and as shown, one short stay has been attached, a long stay is in the act of being applied, together with the tie-wire stock fed to the intersections of said long stay and intermediate strand wires, and in dotted lines is shown the successive step in feeding a short stay wire, after the feeding of each long stay wire.

The end coilers 24 through which the outside marginal or selvage wires of the fence pass, are driven from the timing shaft 10 by means of the bevel gear wheel 147 intermeshing with the bevel gear pinions 148 on the lower ends of said coilers.

On the opposite ends of the timing shaft 10 are carried cam wheels 148 and engaging and riding on the surfaces of said cam 20 wheels are rollers 150 carried by levers 151, fulcrumed at 124 on bracket 68, and to the rear end of each of said levers 151 are pivotally connected bars or rods 152 for operating a pull-out mechanism, not shown. 25 The pull-out mechanism to which the bars or rods 152 are connected is substantially such a mechanism as is shown and described in the Sommer Patent 1,078,702, the same being adapted when moved to intermittently advance or feed the strand wires A through the machine, and adjusted to move said strand wires the distance at which it is desired to place the stay wires from each other to provide the proper spacing between 30 the stay wires on the fabric.

In my former Patent No. 1,093,578, there is shown, described and claimed a mechanism for operating the rack-bar which would feed the stay wire, starting at a slow 40 speed and increasing to the maximum speed, and slowing down to a complete stop, whereby a predetermined and given length of stay wire is fed, without any waste, thus avoiding the severing of short pieces from the stay 45 wire C after the wire is fed. This is accomplished by the use of the particular mechanism shown in that patent for driving the rack-bar from the crank shaft. The mechanism here substituted for driving the rack-bar from the crank shaft will not only permit of the feeding of the stay wires in the manner just stated, but is also adapted, as described, to alternately feed a long and a short stay, embodying in such mechanism 50 the feeding of the stay wire, starting at a slow speed and increasing to the maximum speed and slowing down to a complete stop.

What I claim is:—

1. In a wire fence machine, in combination, strand wire feeding means, a stay-wire feeding mechanism, means for operating said feeding mechanism to cause the same to alternately feed a short stay wire to certain 60 of said strand wires and a comparatively

longer stay wire to all of said strand wires, 65 means for feeding tie-wire stock to the intersections of the short and longer stay wires with certain of said strand wires, and other means for feeding tie-wire stock to the intersections of the longer stay wires 70 with certain other of said strand wires.

2. In a wire fence machine, in combination, strand wire feeding means, a stay wire feeding mechanism, means for operating said feeding mechanism to cause the same to alternately feed a short stay wire to certain 75 of said strand wires and a comparatively longer stay wire to all of said strand wires, two sets of tie-wire stock feeding mechanisms, one set adapted to feed tie-wire stock 80 to the intersections of the short and longer stay wires with certain of said strand wires, the other set adapted to feed tie-wire stock to the intersections of the longer stay wires with certain other of said strand wires, said 85 last mentioned set of tie-wire stock feeding mechanisms operating during each alternate operation of said other tie-wire stock feeding mechanisms.

3. In a wire fence machine, in combination, strand wire feeding means, a stay wire feeding mechanism, including a rack-bar, a crank shaft, a mechanism connected to rotate with said shaft and adapted during such rotation to reciprocate said rack-bar, 95 and means for adjusting said mechanism relatively to said shaft during the rotation thereof for changing the stroke of said rack-bar, whereby said stay wire feeding mechanism will feed alternately a short stay wire 100 and a comparatively longer stay wire.

4. In a wire fence machine, in combination, strand wire feeding means, a stay wire feeding mechanism, including a pair of co-operating feeding wheels, a crank shaft, a 105 mechanism connected to rotate with said shaft and operating connections between said mechanism and said feeding wheels adapted to rotate said wheels, and means for adjusting said mechanism relatively to said 110 shaft during the rotation thereof for varying the rotation of said feeding wheels, whereby said feeding wheels will feed alternately a short stay wire and a comparatively longer stay wire.

5. In a wire fence machine, in combination, strand wire feeding means, a stay wire feeding mechanism, including a rack-bar, a crank shaft, a member connected to rotate with said shaft, an operating bar pivotally 120 connected at one end to said rack-bar, and at its opposite end having a pivotal connection with said member, and means for adjusting the pivotal connection between said operating bar and said member during the 125 rotation of the crank shaft to change the position of said pivotal connection relatively to the axis of said shaft, whereby the stroke

- of the rack-bar may be alternately varied to feed alternately a short stay wire and a comparatively longer stay wire.
6. In a wire fence machine, a stay wire feeding mechanism, including feeding wheels, a rack-bar and operating connections between said rack-bar and said feeding wheels, a crank shaft, a mechanism connected to rotate with said shaft and adapted during such rotation to reciprocate said rack-bar, and means for adjusting said mechanism relatively to said shaft during the rotation thereof for changing the stroke of said rack bar, whereby said feeding wheels will feed alternately a short stay wire and a comparatively longer stay wire.
7. In a wire fence machine, in combination, a stay wire feeding mechanism, including feeding wheels, a rack-bar and operating connections between said rack-bar and said feeding wheels, a crank shaft, a member connected to rotate with said shaft, a plate on said member adjustable toward and from the axis of said shaft, connections between said plate and said rack-bar, and means for adjusting said plate on said member during the rotation of the crank shaft, the adjustment of said plate varying the stroke of the rack-bar, whereby said feeding wheels will feed alternately a short stay wire and a comparatively longer stay wire.
8. In a wire fence machine, in combination, a stay wire feeding mechanism, including feeding wheels, a rack-bar and operating connections between said rack-bar and said feeding wheels, a crank shaft, a member connected to rotate with said shaft, a plate on said member adjustable toward and from the axis of said shaft, connections between said plate and said rack-bar, a revolute part carried by said member, connections between said revolute part and said plate, and gearing for imparting rotative movement to said revolute part during the rotation of the crank shaft for changing the position of said plate relatively to the axis of said shaft, whereby the stroke of said rack-bar may be changed during the rotation of said crank shaft.
9. In a wire fence machine, in combination, a stay wire feeding mechanism, including feeding means, a rack-bar and operative connections between said rack-bar and said feeding wheels, a crank shaft, a member connected to rotate with said shaft, a plate on said member adjustable toward and from the axis of said shaft, connections between said plate and said rack-bar, a revolute part carried by said member, connections between said revolute part and said plate, means for adjusting said last-mentioned connections and fixing the same in adjusted positions, and gearing for imparting rotative movement to said revolute part during the rotation of the crank shaft, whereby the position of said plate relatively to the axis of said shaft is changed during the rotation of the crank shaft, changing the position of said plate relatively to the axis of said shaft, whereby the stroke of said rack-bar may be changed during the rotation of said crank shaft.
10. In a stay wire feeding mechanism for wire fence machines, in combination, stay wire feeding means, a shaft, a member connected to rotate with said shaft, a plate on said member adjustable toward and from the axis of said shaft, operating connections between said plate and said feeding means, means on said member for adjusting the position of said plate relatively to the axis of said shaft during the rotation of said shaft, and means for operating said plate adjusting means.
11. In a stay wire feeding mechanism for wire fence machines, in combination, stay wire feeding means, a shaft, a member connected to rotate with said shaft, a plate on said member adjustable toward and from the axis of said shaft, operating connections between said plate and said feeding means, a part rotatably carried on said member, connections between said part and said plate, and gearing for imparting rotative movement to said part during the rotation of said shaft, such movement of said part adjusting the position of said plate relatively to the axis of said shaft.
12. In a stay wire feeding mechanism for wire fence machines, in combination, stay wire feeding means, a shaft, a member connected to rotate with said shaft, a plate on said member adjustable toward and from the axis of said shaft, operating connections between said plate and said feeding means, a part rotatably carried on said member, connections between said part and said plate, a segment gear having a fixed relation with respect to said shaft, and a gear connected with said rotatable part and adapted to intermittently mesh with said segment gear, for imparting rotative movement to said rotative part during the rotation of said shaft, such movement of said part adjusting the position of said plate relatively to the axis of said shaft.
13. In a wire fence machine, in combination with means for feeding a plurality of intermediate and marginal strand wires, stay wire feeding mechanism, wire connecting mechanism, means for feeding tie-wire stock to the wire connecting mechanism for all of the intermediate strand wires, and means for operating said tie-wire stock feeding mechanism at predetermined intervals to feed tie-wire stock to a predetermined number of said intermediate strand wires.
14. In a wire fence machine, in combination, strand wire feeding means, means for feeding stay wires to said strand wires, means for feeding tie-wire stock to the

intersections of said stay wires with certain of said strand wires, and other means for feeding tie-wire stock to the intersections of said stay wires with certain other of said 5 strand wires.

15. In a wire fence machine, in combination, strand wire feeding means, means for feeding stay wires to said strand wires, means disposed on one side of the machine 10 for feeding tie-wire stock to the intersections of said stay wires with certain of said strand wires, and other means disposed on the opposite side of said machine for feeding tie-wire stock to the intersections of said 15 stay wires with certain other of said strand wires.

16. In a wire fence machine, in combination, strand wire feeding means, coilers through which the marginal strand wires 20 pass, means for feeding stay wires to said strand wires, means disposed on one side of the machine for feeding tie-wire stock to the intersections of said stay wires with certain of the intermediate strand wires, other 25 means disposed on the opposite side of said machine for feeding tie-wire stock to the intersections of said stay wires with certain other of the intermediate strand wires, and guiding tubes for said tie-wire stock, said 30 guiding tubes for a portion of their length extending transversely across the machine and then diagonally to the points of intersection of the stay wires with said intermediate strand wires.

35 17. In a wire fence machine, in combination, strand wire feeding means, means for feeding stay wires to said strand wires, two sets of tie-wire stock feeding mechanisms, one set adapted to feed tie-wire stock to the 40 intersections of said stay wires with certain of said strand wires, the other set adapted to feed tie-wire stock to the intersections of said stay wires with certain other of said strand wires, one set of tie-wire stock feeding 45 mechanisms operating during each alternate operation of said other tie-wire stock feeding mechanisms.

18. In a wire fence machine, tie-wire stock feeding mechanism comprising a driving shaft and a driven shaft, coöperating 50 feeding wheels on said shafts, a pair of ratchet toothed wheels carried on said driving shaft, one secured to said shaft and the other loose thereon, said loose ratchet 55 toothed wheel having teeth corresponding in number to the teeth on said fixed wheel and every other tooth of said loose wheel being a deep tooth, a pawl adapted to engage the teeth of both of said ratchet wheels, but 60 only the teeth of said fixed wheel when said pawl engages a deep tooth on said loose wheel, and means for operating said pawl.

19. In a wire fence machine, tie-wire stock feeding mechanism comprising a driving 65 shaft and a driven shaft, coöperating

feeding wheels on said shafts, a pair of ratchet toothed wheels carried on said driving shaft, a pawl adapted to engage the teeth of said ratchet wheels, and means for operating said pawl, said ratchet toothed 70 wheels being so constructed that with each movement of said pawl one of said wheels will be moved the distance of one tooth, and with each alternate movement of said pawl both of said ratchet toothed wheels will be 75 moved a distance of one tooth and in unison.

20. In a wire fence machine, in combination, a pair of feeding wheels, a gear wheel operatively connected with one of said feeding wheels, said gear wheel having an internally arranged clutch engaging surface, a shaft, a wheel connected with said shaft and having a clutch engaging surface adapted to be moved into and out of engagement with the clutch engaging surface of said 80 gear wheel, means controlling the movement of said last-mentioned wheel, and means for operating said shaft.

21. In a wire fence machine, in combination, a pair of feeding wheels, a gear wheel 90 operatively connected with one of said feeding wheels, said gear wheel having an internally arranged clutch engaging surface, a shaft, a wheel having a clutch engaging surface adapted to be moved into and out 95 of engagement with the clutch engaging surface of said gear wheel, a member connected to rotate with said shaft, connections between said member and said last-mentioned wheel, means controlling the 100 movement of said wheel, and means for operating said shaft.

22. In a wire fence machine, in combination, a pair of feeding wheels, a gear wheel operatively connected with one of said feeding wheels, said gear wheel having an internally arranged clutch engaging surface, a shaft, a wheel having a clutch engaging surface adapted to be moved into and out 105 of engagement with the clutch engaging surface of said gear wheel, a member connected to rotate with said shaft, connections between said member and said last-mentioned gear wheel, means operated through the shaft to move said wheel into and out 110 of clutch engaging relation with said gear wheel, and means for operating said shaft.

23. In a wire fence machine, in combination, a pair of feeding wheels, a gear wheel operatively connected with one of said feeding wheels, said gear wheel having an internally arranged clutch engaging surface, a shaft, a wheel having a clutch engaging surface adapted to be moved into and out 120 of engagement with the clutch engaging surface of said gear wheel, a member connected to rotate with said shaft, connections between said member and said last-mentioned gear wheel, a stem reciprocally arranged 125 within said shaft, connections between said 130

stem and said wheel, whereby when the stem is moved in one direction said wheel will be moved to disengage its clutch engaging surface from the clutch engaging surface of said gear wheel, means for yieldingly returning said wheel to clutch engaging relation with said gear wheel, means for operating said shaft, and means for operating said stem.

24. In a wire fence machine, in combination, a pair of feeding wheels, a gear wheel operatively connected with one of said feeding wheels, said gear wheel having an internally arranged clutch engaging surface, a shaft, a wheel having a clutch engaging surface adapted to be moved into and out of engagement with the clutch engaging surface of said gear wheel, a member connected to rotate with said shaft, connections between said member and said last-mentioned gear wheel, a stem reciprocally arranged within said shaft and connected at one end with said wheel, said stem provided with transverse openings therethrough, a member located within said stem and projecting from the end thereof beyond the gear wheel,

spring means around the end of said member and bearing against said wheel, means for operating said shaft, and means for operating said stem.

30

25. In a wire fence machine, in combination, feeding means for a stay wire including feeding wheels, a shaft, means including a reciprocating member to operate said feeding wheels, means operated by said shaft to control the distance of movement of said reciprocating member, said controlling means having a predetermined action relatively to the rotation of said shaft, whereby said reciprocating member will move a given distance during one stroke and a different distance during another stroke.

35

26. In a wire fence machine, in combination, feeding means for a stay wire, operating means for said feeding means, including a reciprocating member, means for operating said member including means for changing the distance of movement of said member during a given movement of said feeding means.
